UNITED STATES PATENT OFFICE.

ALFRED HUBERT ROY FEDDEN AND LEONARD FREDERICK GEORGE BUTLER, OF BRISTOL, ENGLAND, ASSIGNORS TO THE BRISTOL AEROPLANE COMPANY LIMITED, OF BRISTOL, ENGLAND, A BRITISH COMPANY.

SCREW PROPELLER.

Application filed November 21, 1924. Serial No. 751,308.

To all whom it may concern:

Be it known that we, ALFRED HUBERT ROY FEDDEN and LEONARD FREDERICK GEORGE BUTLER, both subjects of the King of England, and both residing at Bristol, in the county of Gloucester, England, have invented certain new and useful Improvements in Screw Propellers, of which the following is a specification.

10 This invention is for improvements in or relating to screw-propellers of the type known as "feathering" or "variable pitch" propellers, in which the blades are capable of angular adjustment each about its own longitudinal axis, that is to say, about a line extending from the root to the tip of the blade, for the purpose of varying the effective pitch of the propeller. The invention is particularly applicable to propellers 15 or air-screws, such as are used in aircraft, but it is not limited to this particular application of it.

According to this invention there is provided in a variable-pitch propeller, the combination of a driving-shaft, two or more blades carried thereby, and so mounted as to be capable of angular adjustment each about its own longitudinal axis, an operating-shaft formed with a screw-thread 20 whereof the angle, for the purpose later set forth, is small, a nut-member on said operating-shaft operatively engaging the said blades to turn them each about its own axis by a movement of the nut-member along the said shaft lengthwise thereof, and means for producing relative rotation between the nut-member and the operating-shaft to produce the said traversing movement.

The invention also comprises a variable-pitch propeller wherein the operating-shaft is constituted by a screw-threaded portion of or on the driving-shaft, and a nut-member thereon carries a sleeve which receives the axial movement but not the rotational movement of the nut-member, and also is operatively engaged with the blades to vary their effective pitch by the said axial movement.

Furthermore, the invention comprises in 50 a variable-pitch propeller, the combination with the nut-member of means, such as a "hunting" friction-gear, for operatively connecting it to the engine which drives the propeller to effect the changing of the pitch.

According to another feature of this invention the means for rotating the nut-member may comprise a gear-wheel fast on it engaging a gear-wheel driven by a friction-wheel which is adapted to co-operate with a normally stationary part of the engine, with 60 or without a speed-reducing gear between the friction-wheel and the second-mentioned gear-wheel.

More specifically this invention comprises in a variable-pitch propeller, the combination of two rotatable shafts carried by the sleeve aforesaid so as to be moved axially therewith, and situated eccentrically with respect to the driving-shaft, a friction-wheel on each of said shafts, a co-operating friction surface or surfaces on a non-rotating part of the engine adapted to be engaged alternatively with said friction-wheels, by movement axially of the driving-shaft, a gear-wheel on each of said shafts engaging 75 respectively internal and external gears formed on a flange-like member encircling and rotatable on the sleeve, and a double planetary gear carried by said member engaging respectively a gear fast on the sleeve 80 and a gear fast on the nut-member.

Another feature of this invention consists in the arrangement of the gearing aforesaid whereby, for the purpose hereinafter set forth, the movement of the friction-surface 85 aforesaid in one or other direction along the axis of the driving-shaft to set the gear in operation causes the nut-member to be traversed along the driving-shaft in the same direction.

The invention also comprises a variable-pitch propeller as above set forth wherein the friction-surface aforesaid is for the purpose hereinafter described a segment only of a circle; furthermore, the friction-surface 95 may be resiliently mounted, for the purpose hereinafter described.

Other features of the invention relating to the control will be hereinafter described and the novel details pointed out in the claims 100 appended to this specification.

In the accompanying drawings—

Figure 1 is a longitudinal section of the hub of a screw-propeller constructed in accordance with this invention, being a section 105 on the line 1—1 of Figure 2;

Figure 2 is a section on the line 2—2 of Figure 1;

Figure 3 is a part-longitudinal section of a hub showing a modified construction;

Figure 4 is a sectional view of a detail on the line 4—4 of Figure 3; and

5 Figure 5 is a diagrammatic representation of the pilot's controlling gear for the propeller;

Figures 6, 7 and 8 are detail views showing a modified form of operating and 10 controlling gear for the propeller.

Referring first to Figure 1 which illustrates one embodiment of this invention as applied to the air-screw or propeller for an aircraft driven by an internal-combustion 15 engine, the crank-shaft casing of the engine is indicated at 10 and an extension 11 of the crank-shaft constitutes the driving-shaft of the propeller. Upon this shaft 11 there is mounted a hub comprising a sleeve or 20 cylindrical portion 12 and a radial flange 13, and this hub is locked to the shaft 11 to rotate with it. The sleeve portion 12 of the hub is formed on the side of the flange remote from the engine with an irreversible 25 screw-thread 14, that is to say with a thread having a small spiral angle; conveniently this thread is of acme form, although other forms may be used if so desired, and in order to keep the spiral angle small, the 30 thread 14 is preferably a single-start thread.

Upon this screw-threaded sleeve 12, which constitutes the operating shaft for varying the pitch of the propeller, there is mounted a nut-member 15 which takes the 35 form of a sleeve internally-screw-threaded as at 16 to co-operate with the thread 14 aforesaid. The nut-member 15 is axially of less length than the screw-threaded portion of the hub 12 whereon it is mounted, 40 and it can be traversed along it by producing relative rotation between them. On the outer cylindrical surface of the nut-member 15 there is mounted a sleeve 17 which is held against endwise movement on the nut-member 45 between a flange 18 thereon and a nut 19, so that it partakes of the endwise or axial movement of the nut-member but does not partake of the rotation of the nut-member when it is screwed along the hub 50 12, the nut-member 15 turning freely with in the sleeve 17.

A cylindrical casing 20 surrounds the nut-member 15 and sleeve 17 aforesaid and is gripped between the flange 13 and a detachable flange 21 which is screwed on to the outer free end of the hub 12; this casing 20 is preferably also bolted to the flanges 13, 21, so that a positive drive is imparted to it when the flanges rotate.

60 The sleeve 17 is formed at about the middle of its length with a radially-extending flange 22, and a similar flange 23 is provided at the end near the engine. A tubular member 24 is suitably secured in perforations in the flanges and it extends, to the

right in Figure 1, inside an extension-piece 25 on the crank-case 10 of the engine. Any suitable number of these tubular members 24 are provided, two being illustrated in the present instance at 24, 26. Within each of them there is mounted a shaft 27, these shafts being rotatable in suitable bearings 28, 29 and each carrying at the end remote from the engine a small gear-wheel 30, 31 respectively. An annular flange-like member 32 is rotatably mounted on the sleeve 17 in such manner as to partake of the endwise movement of the sleeve 17, and this flange-like member is provided with two sets of gear-teeth, an internal set 33 and an external set 34. The internal set of teeth 33 mesh with the gear-wheel 31 aforesaid, whilst the external teeth 34 mesh with the companion gear-wheel 30 aforesaid. This arrangement provides that if one or other 85 of the shafts 27 is rotated in one direction, the annular flange-like member 32 is rotated in one or other direction on the sleeve 17.

This member 32 also carries one or more 90 double planetary pinions 35, 36 which mesh respectively with a gear-wheel 37 fast on the sleeve 17, and a gear-wheel 38 fast on the nut-member 15. The whole thereby constitutes an epicyclic train of gearing whereby rotation of the flange-member 32 in one direction or other imparts relative rotation to the sleeve 17 and the nut-member 15. The sleeve-member 17 cannot rotate relatively 95 to the flange 13 and hub 12, and the relative movement aforesaid is therefore a relative movement between the nut-member 15 and the hub 12, so that the nut-member is traversed along the hub 12 in one direction or the other according to the direction of 100 rotation of the flange-member 32.

In order to provide for driving one or other of the shafts 27 aforesaid, each of these shafts carries at the end near the engine a friction-wheel 39, 40 respectively, 105 these wheels lying within the extension 25 of the crank-case aforesaid. A friction-surface 41 to co-operate with these wheels is arranged inside the part 25 aforesaid and is movable lengthwise of the shaft. Conveniently a single friction-surface 41 in cylindrical form is provided and the two wheels 39, 40 are displaced lengthwise of the driving-shaft 11 so as to lie one on each side of it. The friction-surface 41 is movable endwise to engage one or other of these wheels, that is to say in Figure 1 if it is moved towards the right it engages the wheel 39, and if it is moved towards the left it engages the wheel 40. It will be appreciated that when the shaft 11 is in rotation the whole of the mechanism is carried round with it, including the wheels 39, 40, and by their engagement with the stationary friction-surface 41 a drive is imparted alternatively to 115 120 125 130

them, the direction of the drive being the same in both cases.

The train of gearing, consisting of the friction-surface 41, friction-wheel 39 (or 40), gear-wheels 30, 34 (or 31, 33), 35, 37, 36, 38, is so arranged that when the friction-surface 41 is moved to engage one or other of the friction-wheels 39, 40, the resulting axial movement which is given to the nut-member 15 is such that it is traversed axially in the same direction as the friction-surface 41 was originally moved; this movement will continue until the corresponding friction-wheel is carried just clear of the friction-surface. That is to say, assume the friction-surface is moved to the left in Figure 1, it will engage the wheel 40 and set the gear in motion so that the nut-member 15 is traversed to the left, and this traversing movement continues until the wheel 40 is carried just clear of the friction-surface 41. Further, it will be appreciated that the wheel 39 partakes of the same axial movement as the wheel 40, so that in the final position the relative setting of the friction-wheels and the friction-surface is the same as in the original position. This, of course, necessitates that the traversing movement of the nut-member 15 is exactly equal to the movement imparted to the friction-surface, 41.

It will be appreciated that the drive is imparted to one or other of the wheels 39, 40 by their engagement with the friction-surface 41, the wheels being carried around by the rotation of the shaft 11. The power required for traversing the nut-member is therefore derived in the first instance from the engine which turns the shaft 11, and the amount of traversing movement is controlled manually by the longitudinal movement of the friction-surface 41.

Turning now to Figure 2 which, as above mentioned, is a sectional view on the line 2-2 of Figure 1, the flange 22 aforesaid on the sleeve 17 has formed on it a series of lugs 42, one for each of the blades of the propeller. These lugs are each bored to receive a hardened steel pin 43 which is situated with its axis transverse to that of the driving-shaft 11. Each of these pins carries at one end a square bush 44 which is received in a straight-sided U-shaped slot 45 so that it is free to move therein, this movement in Figure 2 being in a vertical direction. This slot is formed on the end of an arm 46 which extends from a ring-shaped bearing-member 47.

The cylindrical casing 20 aforesaid is provided with tubular bosses 48 for each of the blades of the propeller. The root end of each blade is suitably secured in a metal socket 49, and this socket is located in one of the bosses 48 by means of two bearings. The radially inner bearing is preferably a

ball-bearing of the cup-and-cone type, which permits free rotation of the socket 49 and also provides effectively for absorbing any end-thrust on the blade due to centrifugal force whilst the propeller is in rotation. 70 This bearing is constituted by the ring 47 aforesaid and a second ring 50, these being secured respectively on the socket 49 and on the casing 20.

The radially outer bearing for the socket 75 is indicated at 51, and it may be a roller-bearing or a plain sleeve bearing, its function being merely to act as an additional guide for the socket.

In the operation of this device, axial 80 movement of the sleeve 17 and its flange 22 produces a rotational movement of each propeller blade about its longitudinal axis, owing to the engagement of the pin 43 with the slot on the end of the arm 46. The pin 85 43 has a straight-line movement normal to the surface of the paper in Figure 2, and the arm 46 has, of course, a circular movement about the axis of the propeller blade. The construction of bush 44 and slot 45, however, permits the desired movement to take place, it being appreciated that the angular movement of the propeller blade about its own axis is not required to be of very great extent. The endwise movement of the sleeve 17 and flange 22 is obtained in the manner above described by traversing the nut-member 15 along the hub 12, and it will be appreciated that by using an irreversible thread 14 of small spiral angle, the mechanism is self-locking in any position, that is to say the angular setting of the blades cannot be altered by any pressure or force applied directly to them. The whole of the thrust on the blades, which is due to their setting or obliquity and which tends to rotate them about their respective longitudinal axes, is taken up on the screw-thread 14, and there is no transmission of this thrust to the mechanism whereby the pitch of the blades is 100 adjusted. The pitch of the propeller can therefore be altered only by rotating the nut-member 15 on the hub 12, and this operation is controlled only by the pilot of the aircraft (by adjustment of the friction-surface 41) in the manner hereinbefore described. 105

It will be appreciated that an air-screw normally rotates at high speeds, and any adjustment of the pitch of the blades should be made only gradually; it is for this reason, therefore, that the epicyclic train of gears is introduced in the construction illustrated in Figure 1. Figure 3 illustrates a modified construction whereby the necessary speed reduction can be obtained. In this case the annular flange-like member 52, which corresponds to the member 32 of Figure 1, is keyed directly to the nut-member 15, and it carries internal and external gears 115 120 125 130

as before. These gears are driven as before by the pinions 30, 31, of which only one is shown, and the pinions themselves are driven by the friction-wheels 39, 40 also in the same way. Instead of providing a friction-surface which is in the form of a complete cylinder, however, it is of segmental form, as shown at 53. By this means the friction-wheels engage it only during a small part of each rotation of the driving-shaft 11. The traversing movement imparted to the nut-member is of course intermittent, but the desired speed reduction is obtained without the use of gearing. The friction-surface 53 is preferably resiliently mounted, as shown in Figures 3 and 4, being provided with a spring 54 which normally presses it radially inward and allows it to yield outwards when the friction-wheels come in contact with it. The surface which the wheels engage may be flat or curved to a larger radius than the circle on which the outermost part of the friction-wheels travels. The shock of the impact of the friction-wheels on it is thereby reduced, and the drive is gradually taken up by these wheels whilst they are in contact with it. Obviously, instead of mounting the member 53 resiliently, the bearing near the wheel 39 could be resiliently mounted, or, alternatively, the friction-wheel itself may be provided with a suitable resilient peripheral member, such for example as rubber or spring steel.

This friction-member 53 is controlled in the same way as the part 41 of Figure 1, and is illustrated as being moved endwise by a controlling handle 55 against the action of a spring 56, but it will be appreciated that these details may be modified in any desired manner. The arrangement of the friction-surface 41 or 53, with its two cooperating friction-wheels 39, 40, constitutes a "hunting" gear, and it will be appreciated that various other devices may be used, including a servo-motor, to obtain a similar result.

The other details of the construction illustrated in Figure 3 are similar to the construction illustrated in Figure 1 and need not be described again in detail.

Instead of using a drive through friction-wheels as above described for effecting the adjustment of the propeller-blades, the mechanism illustrated in Figures 6, 7 and 8 may be used. Figure 6 is a view corresponding to the right-hand part of Figure 1, Figure 7 is a plan partly in section of Figure 6, and Figure 8 is a section on the line 8-8 of Figure 7. The tubular member 24 in Figure 6 corresponds with the member 24 in Figure 1, as also does the shaft 27. This shaft is mounted to rotate, in Figure 6, in a ball-bearing 66 mounted in a suitable housing 67 which is secured to the tubular member 24 by means of a sleeve 68. On the end of the shaft 27 there is mount-

ed a gear-wheel 69 which meshes with an internally-toothed ring 70. The corresponding shaft 27 in the tubular member 24 at the lower part of the figure is similarly mounted and carries a gear-wheel 71 which meshes with a second internally-toothed ring 72. These two rings are mounted on roller-bearings 73 which are supported in suitable flanges 74 on the propeller hub, so that whilst the rings 70, 72 normally rotate with the propeller hub either of them can be retarded or held so as to rotate relatively to the propeller hub.

The two rings 70, 72 are provided with outwardly-extending flanges which face one another and carry on their opposed faces a lining of a suitable friction material 75, 76.

Turning now to Figures 7 and 8, it will be seen that the brake-shoes 77 are mounted between the two friction-surfaces 75, 76 in such manner that they can be engaged with either one of them; the brake-shoes 77 are mounted upon levers 78 which are free to swing on a shaft 79. As shown in Figure 7, each lever 78 is provided with an upward extension 80 which lies within a housing 81, and compression-springs 82, 83 engage opposite sides of this extension 80 through thimbles 84, 85 respectively. A pin 86 is secured in the housing 81 between tail-pieces on the thimbles 84, 85 so that it will engage one or other of these tail-pieces when relative movement takes place between the housing 81 and the part 80 of the lever 78. One of the housings 81 is provided with an upward extension 87 which constitutes the controlling lever for the mechanism corresponding to the controlling lever 55 of Figure 3. This lever 87 with the housings 81 is fast on the shaft 79 aforesaid, so that movement of the lever 87 rocks both housings.

The operation of this mechanism is as follows. Suppose that the upper end of the lever 87 is moved to the right in Figure 7, it rocks the housings 81 and each spring 82 is therefore compressed and exerts a pressure on the thimble 84 and through it on the part 80 of the lever 78. Simultaneously each pin 86 engages the tail-piece on the thimble 85 and moves the left-hand end of the spring 83 towards the right whilst the right-hand end of the spring is moving towards the right with the housing 81. The pressure of the spring 83 on the part 80 of the lever 78 is thereby entirely relieved. The net result of this movement of the lever 87 is that pressure is exerted upon the lever 78 to move it in such a direction that the brake-shoes 77 are pressed against the friction-surface 75 of the ring 70 and thereby retard its movement. A drive is thereby imparted to the gear-wheel 69 whilst the companion gear-wheel 71 is left free and the blades of the propeller will be adjusted accordingly in

the manner hereinbefore described. This adjustment carries all the gearing and the rings 70, 72 bodily, axially of the hub; this movement continues so long as the spring 5 82 exerts any pressure on the part 80 of the lever 78 and therefore depends upon the extent of the initial movement of the lever 87. As soon as the lever 78 has moved into a position in line with the lever 87, the 10 two springs 82, 83 become balanced and therefore inoperative and the system is in equilibrium again and the brake-shoes 77 are not pressed upon the friction surface 75 of the ring 70 and the motion therefore 15 stops.

A reverse movement of the lever 87 causes the ring 72 to be retarded so that the drive is imparted through the gear-wheel 71 to the adjusting mechanism of the propeller 20 blades in the reverse direction. It will be seen therefore that this mechanism is exactly similar in its operation to the mechanisms previously described.

One of the factors to be considered when 25 selecting the pitch to which a propeller or air-screw on an aircraft should be adjusted, is the density of the atmosphere wherein it is working; it will be appreciated that the principal variation in density arises from 30 variations in the height of the aircraft, and it is important that the pitch should never be reduced to such a degree as will permit the speed of the engine to increase to a dangerous amount. Moreover, there will usually be a maximum effective pitch at which 35 the highest efficiency of the engine will be obtained, and these minimum and maximum values will vary with the density of the atmosphere.

40 The question of determining the permissible pitch for the propeller is of the greatest importance when engines of the super-charging type are used, that is to say, engines in which the pressure of the air supplied to the carburetor is maintained by a blower at the normal pressure existing at ground level, independently of the altitude of the aircraft. The power developed by 45 the engine does not diminish as the density of the air in which the propeller is working diminishes, and it is therefore essential to increase the effective pitch of the propeller when the engine is run at full throttle at 50 high altitudes.

55 As above stated, the pitch of the propeller is changed by means of power drawn from the engine under the manual control of the pilot, the operation effected by the pilot being the longitudinal movement of the 60 friction-surface aforesaid, and this movement is conveniently effected by means of a small control-lever. This lever will be provided with a suitable indicator or scale whereon the maximum and minimum permissible pitches are shown. An-

other feature of this invention has for its object to provide a construction whereby compensation for varying density of the atmosphere is automatically provided, and according to this feature of the invention 70 there is provided the combination with an operating or controlling handle whereof the movement determines the variation in pitch of the propeller, of an indicator showing the maximum and minimum permissible 75 pitch and means for automatically adjusting said indicator in accordance with the power developed by the engine, and/or the density of the medium in which the propeller is working.

More specifically this invention comprises the combination of a control-lever swinging over an indicator or scale, a flexible diaphragm subjected to atmospheric pressure on one side and on the other side to the 80 pressure of the induction system of an internal-combustion engine driving the propeller, and an operative connection whereby the movements of the said diaphragm 85 impart to the indicator a movement or adjustment relatively to the control-lever.

90 Figure 5 illustrates a simple embodiment of this feature. The pilot's control lever 57 is pivotally mounted at 58 and connected by a rod 59 directly or indirectly to the friction-surface aforesaid, being, for example, connected to the lever 55 of Figure 3. A segmental plate 60 is mounted to turn on the spindle 58, and it is operatively connected by a pinion 61 and rack 62 to a pressure-operated device, such as a flexible diaphragm 63 forming one wall of a chamber 64. The interior of the chamber 64 is in communication with the induction system of the engine, and on the outside it is subject to the pressure of the atmosphere. The segment 60 is provided with two marks between which the control-lever 57 may be moved to give the maximum or minimum 95 permissible pitch of the propeller, and a rack 65 may also be provided to lock the lever in any position to which it is adjusted. With the arrangement illustrated, a decrease 100 in atmospheric pressure causes the diaphragm 63 to move upwards in Figure 5 and thereby turns the pinion 61 and the segment 60 in an anticlockwise direction. The maximum permissible pitch of the propeller is increased under these conditions and this 105 increase is shown by the movement of the "maximum" mark in the direction in which the control-lever 57 is moved for increasing the pitch. Simultaneously, of course, a decrease in the atmospheric density raises the minimum permissible value of the pitch, 110 since the speed at which the engine can safely run is limited, and this limitation is also provided for by the simultaneous movement of the "minimum" mark on the segment 60. Obviously, this arrangement may 115 120 125 130

be used in connection with any control-member whereof the setting determines the pitch to which the blades of the propeller are adjusted.

5. What we claim as our invention and desire to secure by Letters Patent is:—

1. In a variable-pitch propeller, the combination of a driving-shaft, a plurality of blades carried thereby and so mounted as to 10 be capable of annular adjustment each about its own longitudinal axis, an operating-shaft, a screw-thread of small spiral angle formed thereon, a nut-member on said screw-thread, means connecting said nut-member to said blades to turn them each about its own axis by a movement of the nut-member lengthwise of the operating-shaft, and means for producing relative 15 rotation between said nut-member and said operating-shaft to produce said lengthwise movement.

2. In a variable-pitch propeller, the combination of a driving-shaft, a plurality of blades carried thereby and so mounted as to 20 be capable of angular adjustment each about its own longitudinal axis, a screw-threaded part on said driving-shaft, a nut-member on said screw-threaded part, a sleeve rotatably mounted on said nut-member, means holding 25 said sleeve against rotation with said nut-member but permitting its axial movement therewith, means connecting said sleeve to said blades to impart angular movement thereto each about its own longitudinal axis 30 by lengthwise movement of the said sleeve along said driving-shaft.

3. In a variable-pitch propeller, the combination of a driving-shaft, a plurality of blades carried thereby and so mounted as 35 to be capable of angular adjustment each about its own longitudinal axis, a part on said driving shaft having a screw-thread of small spiral angle formed on it, a nut-member on said screw-thread, means connecting 40 said nut-member to said blades to turn them each about its own axis by a movement of the nut-member lengthwise of the said screw-threaded part, a power-unit for rotating said driving-shaft, means operable at will 45 for connecting said nut-member to said power-unit to produce relative rotation between the nut-member and the screw-threaded part engaged by it.

4. In a variable-pitch propeller, the combination of a driving-shaft, a plurality of blades carried thereby and so mounted as to 50 be capable of angular adjustment each about its own longitudinal axis, a part on said shaft having a screw-thread of small spiral angle formed on it, a nut-member on said screw-thread, means connecting said nut-member to said blades to turn them each about its own axis by a movement of the nut-member lengthwise of the operating-shaft, a power-unit for rotating said driv- 55

ing-shaft, and a hunting friction-gear operable at will for operatively connecting said nut-member to said power unit to produce relative rotation between the nut-member and the screw-threaded shaft engaged by it. 70

5. In a variable-pitch propeller, the combination of a driving-shaft, a plurality of blades carried thereby and so mounted as to be capable of angular adjustment each about its own longitudinal axis, a part on said shaft having a screw-thread of small spiral angle formed on it, a nut-member on said screw-thread, means connecting said nut-member to said blades to turn them each about its own axis by a movement of the nut-member lengthwise of the operating-shaft, a power-unit for rotating said driving-shaft, a gear-wheel fast on said nut-member, a second gear-wheel engaged thereby, a friction-member rotatively connected with said second gear-wheel and having a rotary movement relatively to said power-unit, and a friction element carried by said power-unit, and movable at will into engagement with said friction-member. 80

6. In a variable-pitch propeller, the combination of a driving-shaft, a plurality of blades carried thereby and so mounted as to be capable of angular adjustment each about its own longitudinal axis, a part on said shaft having a screw-thread of small spiral angle formed on it, a nut-member on said screw-thread, means connecting said nut-member to said blades to turn them each about its own axis by a movement of the nut-member lengthwise of the operating-shaft, a power-unit for rotating said driving-shaft, a gear-wheel fast on said nut-member, a friction-wheel having a rotary movement relatively to said power-unit, a speed-reducing gear rotatively connecting said friction-wheel with said gear-wheel, and a friction-element carried by said power unit and movable at will into engagement with said friction-wheel. 100

7. In a variable-pitch propeller, the combination of a driving-shaft, a plurality of blades carried thereby and so mounted as to be capable of angular adjustment each about its own longitudinal axis, a part on said shaft having a screw-thread of small spiral angle formed on it, a nut-member on said screw-thread, means connecting said nut-member to said blades to turn them each about its own axis by a movement of the nut-member lengthwise of the operating-shaft, a power-unit for rotating said driving-shaft, a gear-wheel fast on said nut-member, two rotatable shafts carried by said nut-member and situated eccentrically 115 with respect to the driving-shaft, a pinion on each of said shafts engaging said gear-wheel, a second pinion on each of said shafts, two friction-wheels each operatively engaged 120 with a gear-wheel which last-mentioned 125

100

105

110

115

120

125

130

gear-wheels respectively engage said second-mentioned pinions, and a friction-element carried by said power-unit and movable at will to engage said friction-wheels alter-
5 natively.

8. In a variable-pitch propeller, the combination of a driving-shaft, a plurality of blades carried thereby and so mounted as to be capable of angular adjustment each
10 about its own longitudinal axis, a part on said shaft having a screw-thread of small spiral angle formed on it, a nut-member on said screw-thread, means connecting said nut-member to said blades to turn them each
15 about its own axis by a movement of the nut-member lengthwise of the operating-shaft, a power-unit for rotating said driving-shaft, a gear-wheel fast on said nut-member, two rotatable shafts carried by said
20 nut-member and situated eccentrically with respect to the driving shaft, a pinion on each of said shafts engaging said gear-wheel, a second pinion on each of said shafts, two

friction-wheels each operatively engaged with a gear-wheel which last-mentioned 25 gear-wheels respectively engage said second-mentioned pinions, and a friction-element carried by said power-unit and movable at will to engage said friction-wheels alter-
natively, said gears being so disposed that 30 the movement of the nut-member resulting from the engagement of the friction-element aforesaid with one of said friction-wheels carries the nut-member and gearing aforesaid longitudinally of said driving-shaft in 35 such direction as to disengage the operative friction-wheel from the friction-element aforesaid.

In testimony whereof we have signed our names to this specification in the presence 40 of two subscribing witnesses.

ALFRED HUBERT ROY FEDDEN.

LEONARD FREDERICK GEORGE BUTLER.
